Filed Nov. 1, 1957, Ser. No. 693,843

25 Claims. (Cl. 101—44)

This invention relates to ware decorating apparatus for automatically decorating dishware and the like in the course of its manufacture.

An object of the invention is to provide automatic decorating equipment in which a number of decorating units, such as stamping units and spraying units, can be readily organized and reorganized to operate on the ware in any one of a large number of different sequences.

Another object of the invention is to provide ware advancing and indexing apparatus for advancing the workpieces or ware which are being decorated from one decorating unit to the next while properly maintaining the ware in centered position and (1) rotating it in a datum rotative position or (2) rotating it to and from such position at each unit according to a program which is readily preselected for each production run according to the requirements of the sequence of decorating operations chosen for that production run.

Another object of the invention is to provide ware-decorating apparatus having ware advancing and indexing means which can be expanded indefinitely by rebuilding to accommodate any desired increased number of decorating steps, all without obsoleting any of the equipment existing prior to the rebuilding, whereby apparatus embodying the invention may be built according to current requirements without necessitating any commitment limiting the number of decorating operations with which the same apparatus may be associated in the future.

Another object of the invention is to provide ware-decorating units each of which may be readily associated and disassociated from ware advancing and indexing apparatus at any one of a number of decorating stations.

Another object of the invention is to provide improved apparatus for stamping decorations onto ware.

Another object of the invention is to provide improved apparatus for spraying decorations onto ware.

Other objects and advantages of the invention will appear from the following description of an existing example of the invention.

In the drawings:

Figure 1 is a general plan view of the indexing apparatus forming the larger structural portion of the invention, shown somewhat schematically.

Figure 33 is a plan view of the line 33—33 in Figure 32. (It is shown on the same sheet as Figure 15.)

Figure 34 is a schematic side elevational view of spray decorating apparatus for use with the indexing apparatus shown in Figures 1—33.

Figure 35 is a front elevation of Figure 34.

Figure 35A is a fragmentary section on the line 35A—35A in Figure 35.

Figure 36 is a plan view in section on the line 36—36 of Figure 35.

Figure 37 is an enlarged plan view in section approximately on the line 37—37 of Figure 35.

Figures 38 and 38A constitute the side elevation in enlarged scale of Figure 34.

Figure 39 is a sectional view on the line 39—39 of Figure 37.

Figure 40 is a sectional view on the line 40—40 in Figure 37.

Figure 41 is a schematic side elevational view of the stamp decorating device for use with the indexing apparatus shown in Figures 1—33.

Figures 42 and 42A constitute a side elevation of Figure 41 with parts broken away.

Figures 43 and 43A constitute a rear elevation of Figure 41.

Figure 44 is a plan view of Figure 41.

Figure 45 is a plan view in section on the line 45—45 of Figure 42.

Figure 46 is a section on the line 46—46 of Figures 43 and 43A.

Figure 47 is a section on the line 47—47 of Figures 41 and 42.

Figure 48 is a plan view on the line 48—48 of Figure 43A.

Figure 49 is a sectional plan view on the line 49—49 in Figure 42.

Figure 50 is a schematic view of a typical hydraulic control system for one of the hydraulically actuated elements of the invention.

General organization of the indexing apparatus

In the following description of the illustrated embodiment of the invention, the various parts will be designated by reference numerals, and, in many instances, the figures in which those parts may be most conveniently found will be designated parenthetically. For example, when reference is made to a "drive chain 13 (1, 3, 4, 21, 27)," the part or parts in question are indicated by the reference numeral 13 in the drawings and may be most conveniently or clearly found in Figures 1, 3, 4, 21 and 27.

The indexing mechanism is illustrated in Figures 1-33. Decorating units appropriate for use with the indexing mechanism are illustrated in the remaining drawings. The indexing mechanism illustrated in the drawings involves the cycling of elements around an elongated loop or path rather than around a circular loop or path, as clearly seen in Figure 1. The elongated loop or path is generally preferred inasmuch as it makes possible the subsequent expansion of the capacity of the equipment by merely adding decorating stations and increasing the distance between the ends of the equipment. Such alterations, of course, are not intended to be made frequently, but the possibility of making them greatly increases the flexibility of the equipment. It is to be understood, however, that some aspects of the invention are applicable to circular path or rotary (i.e., turntable type) indexing apparatus.

The apparatus is shown in Figure 1 located adjacent a conveyor generally indicated by the reference numeral 11 and conveying in the direction indicated by the arrow in Figure 1. The conveyor 11 will be understood to be a conventional conveyor, such as a belt conveyor. The structural details of the illustrated indexing mechanism itself may be most conveniently regarded with reference to a basic frame element, such as the main table plate 10 (1-7, 9, 13, 17, 20-26, 31, 32). Associated with the indexing mechanism are the indexing stations indicated in Figure 1 and identified as follows:

I—loading station	VI—idle station
II—idle station	VII—idle station
III—centering station	VIII—decorating station
IV—decorating station	IX—decorating station
V—decorating station	X—unloading station

The indexing apparatus itself (that is, the indexing loop seen in Figure 1) is of first importance and will be initially discussed. There will later be discussed the mechanism for feeding the undecorated ware from the conveyor 11 to the indexing mechanism and for returning decorated ware to the conveyor 11. This mechanism which is to be later described deposits ware at the loading station I and picks up ware from the unloading station X. However, in connection with certain aspects of the invention, it will be understood that this operation could be performed, at some disadvantage, with alternative kinds of apparatus or even manually.

The several parts of the apparatus to be described below are in general actuated by hydraulic cylinders of well-known kinds which are positively hydraulically urged in both their forward and return directions and which are controlled by solenoid-operated hydraulic valves which act to reverse the porting of the hydraulic cylinders and thereby reverse the direction in which they act. The solenoid valves controlling the various hydraulic cylinders are controlled by switches actuated by followers engaging timing cams which are arranged on one or more synchronized shafts. Stated more briefly and in other words, the actuation in each direction of all of the various hydraulic cylinders is initiated from a master timer through solenoid controlled valves in a well-known manner which will be obvious to those familiar with machine design. A typical control system for one hydraulic cylinder is illustrated in Figure 50. A timing cam 1 which is part of a number of cams keyed to the timing shaft 2 is engaged by a follower 2A which actuates control switches 3 and 4 which in in turn control a self-centering solenoid-operated hydraulic valve 5 of a type which will be well-known to those familiar with hydraulic controls for machine parts. The control valve 5 includes a pair of oppositely acting solenoids 5A and 5B which are energized in alternation, depending upon the position of the switch 4, and a spring or springs 5C which position the valve in its neutral position at which all ports are cut off when neither one of the solenoids 5A or 5B is energized, as when the circuit connection to the line L₂ is cut by opening a switch 6. In the position of the parts shown in Figure 50, the follower 2A is in down position or normal position from which it will be understood that the switch 3 is a normally closed switch and the switch 4 is a normally open switch. With the parts in the position shown, the hydraulic cylinder which is being controlled is in its retracted position. When a high point on the timing cam or control cam 1 forces the follower 2A up, the switch 3 is open and the switch 4 is closed. The solenoid 5B is thereby de-energized and the solenoid 5A is energized to reverse the position of the solenoid control valve 5, causing the hydraulic cylinder to extend. When the follower 2A is subsequently allowed by the cam 1 to drop, the switches 3 and 4 de-energize the solenoid 5A and energize the solenoid 5B causing the cylinders to retract. As previously mentioned, when the switch 6 is open, or if for other reasons, such as power failure due to overloading or shorting of the line, neither of the solenoids is energized, the valve 5 is centered by the action of the spring or springs 5C cutting off all hydraulic ports within the valve 5 and instantaneously locking the cylinder in its exact position at the moment of centering of the valve 5. This is a safety precaution so that unwanted and improperly co-ordinated movements of the complex overall mechanism will not occur in the event of power failure or other breakdown.

If it is desired that the hydraulic cylinders controlled by the cam 1 not be actuated during operative cycles of the overall apparatus, a switch 7 is reversed from its illustrated position. This has the effect of cutting solenoid 5A out of the circuit and leaving solenoid 5B energized at all times during which the overall circuit is energized.

A plurality of nests are indexed consecutively past the several stations I to X. Each of these nests is indicated generally by the reference numeral 12 (1, 3, 4, 7, 13, 14, 20, 21, 23-25, 27-31). The nests 12 are linked together in a closed loop by the drive chain 13 (1, 3, 4, 21, 27). They are supported on rollers which engage an outer rail 14 and an inner rail 15 (1, 3, 7, 21). The nests 12 are connected to a vacuum source through vacuum lines 16 (1, 3, 4, 21, 24-26, 28, 29) which, in turn, are supplied from a main vacuum supply line 17 (32).

Nest structure

The structural details of the nests may be best seen in Figures 20-30. Each nest comprises a nest body 20

(20, 21, 24, 25, 27-30) in which is supported a rotatable ware chuck generally indicated by the reference numeral 21 (24, 25, 30). The ware chuck 21 includes ware-gripping means in the form of a vacuum cup 22 (20, 24, 25, 27) and face ribs 23 (20, 21, 24, 25). Mounted on the next body for bodily translation therewith is a drive linkage for rotating the chuck 21. This linkage comprises a gear 24 (21, 22, 24, 25, 31) keyed to an extension 25 (24, 25) or tail shaft which forms part of the structure of the rotatable ware chuck 21.

The vacuum cup 22 is carried on a sliding hollow shaft 27 at the bottom of which is provided a vacuum slip coupling 28 (21, 24, 25, 31). Vacuum at the slip coupling is maintained by a sealing ring 31 (24) in a manner which will be apparent from the drawings. The body of the vacuum slip coupling 28 is held against rotation by the engagement of its integral finger 29 (24-26) with a slot 30 formed in an extension of the nest body 20.

The vacuum line 16 which communicates with the vacuum slip coupling 28 leads from vacuum valve 32 (24, 25, 31) carried bodily on nest body 20. The input vacuum line 16 communicating with the valve 32 leads from a vacuum chamber 33 formed within the body 20. The vacuum lines which lead from one vacuum nest to another also communicate with the vacuum chamber 33 (24, 25) as most clearly illustrated in Figures 24 and 25. The vacuum chamber 33 merely provides a convenient way of manifolding the vacuum at each nest. The shaft 27 slides in sleeve bearings with respect to rotating chuck 21, as most clearly seen in Figures 24 and 25, and is held against relative rotation by a radial extension 37 (25, 28) which is interengaged with a projection 38 carried by the rotatable chuck 21.

The hollow shaft 27 is normally in down position, to which it is urged by the spring 39. It is capable of being raised by being engaged by a plunger 40 associated with a hydraulic cylinder 41 (2, 7, 31) located at loading station I, centering station III and unloading station X.

At each decorating station is provided a drive for the chuck rotating linkage gear 24. Each of these drives comprises hydraulic cylinder 46 (22, 26), rack 47, pinion 48, gear 49 (21, 22, 24, 26), pinion 50 (21, 22, 24), and spur gear 51. The pinion 50 and the spur gear 51 are fixed to a shaft 52 (21, 22) and are mounted therewith for bodily vertical translation. The shaft 52 is mounted in plates 53 which form part of a vertically reciprocating structure which slides in the keyway 54 in a manner which will be apparent from the drawings. The vertical translation of the pinion 50 and spur gear 51 is accomplished by engagement of the lower part of the assembly which slides in the keyway 54. A plunger 56 which is actuated by a hydraulic cylinder 57 engages the assembly which slides in the keyway 54 and which includes the pinion 50 and spur gear 51. The vertical movement of the spur gear 51 is such that it is in engagement, in its raised position, with the spur gear 24 carried on a nest 20 which is at the associated station.

When the spur gear 51 is moved to its raised position, its upper face engages a roller 59 (21) carried on a downwardly urged spring loaded vertically sliding member 62 which is mounted on the underside of the nest body 20. The member 62 also carries a tooth 64 which, in the extended or lowered position of the member 62, is in engagement with the gear 24. The relation of the parts is such that as the spur gear 51 is raised and engages the gear 24, the following engagement of the roller 59 on the face of the gear 51 causes the tooth or detent 64 to be raised out of engagement with the gear 24. Conversely, as the gear 51 is lowered out of engagement with the gear 24, the detent 64 reengages the gear 24. Engagement of each of the members 64 and 51 occurs prior to disengagement of the other so that the gear 24 is, at all times, locked to either the non-rotating member 64 or to the rotating gear 51 which is, of course, controlled by a

positive displacement hydraulic linkage. Accordingly, it will be apparent that at all times the rotated position of the ware chuck associated with the nest 12 is positively determined.

It is to be noted that Figure 25 illustrates not only the raised and engaged position of the spur gear 51 but also the raised position of the shaft 27 and associated vacuum cup 22 which is effected by a plunger 40 associated with the loading, centering, or unloading stations. Also Figure 10 25 shows the rotatable ware chuck and associated elements in a different rotative position from that shown in Figure 24.

The vacuum valve 32 associated with each nest is mounted on the nest body and is controlled by a spring-loaded follower 58 (24-26, 31) which is slidably mounted as is most clearly shown in Figure 26. Vacuum is on when the follower 58 is extended and is off when the follower is raised. The follower 58 is adapted to be raised and lowered at the loading station I, the centering station 15 III and the unloading station X by a plunger 60 associated with a hydraulic actuating cylinder 61 (2, 7, 31) located at each of these stations. Extending from the unloading station to the loading station on the top side of the main table plate 10 is a cam bar 63 (2). It will be understood that the plungers 60 at the unloading and loading stations form in their raised position extensions of the cam bar 63. Thus, a follower 58 which is urged upwardly by the plunger 60 at the unloading station to shut off the vacuum valve 52 and port the associated vacuum cup 30 22 to atmosphere is maintained in such closed position as the nest is then indexed from the unloading station X to the loading station I prior to the time the plunger 60 at the unloading station X is subsequently lowered. If the plunger 60 at the loading station I is also raised, it will be understood that the vacuum shut off is maintained during the latter portion of the dwell of the nest at the unloading station, during the translation of the nest from the unloading station to the loading station and during the initial portion of the dwell of the nest at the loading 35 40 station.

Nest drive and indexing linkages

The chain 13 is powered by drive sprocket 65 (1, 17) and also carried on idler sprocket 66 (1). The drive sprocket 65 is fixed to the shaft 67 (16-19) to which is 45 also keyed a notched drive wheel 68 having notches in which engages a drive pawl 69 which is engaged and disengaged by actuation of a hydraulic cylinder 70 (16, 18, 19) through a bell crank linkage pivoted at the pivot point 71. The other end of the hydraulic cylinder 70 is pivotally mounted at the point 72. The pivot points 71 and 72 are associated with a carrier 73 fixed to a spur gear 74 (16-19) rotatably mounted on the shaft 67. The spur gear 74 is engaged by a rack 75 which is powered by a hydraulic cylinder 76 (16). A holding pawl 78 (16, 55 17) is extended and retracted by a hydraulic actuating cylinder 79 which is mounted on a fixed portion of the frame. The travel of the actuating cylinder 76 and rack 75 is such that the chain 13 is advanced a distance equal to the distance between the several stations around the indexing table each time the actuating cylinder 76 and rack 75 are advanced while the pawl 69 is engaged in one of the notches in the wheel 68.

Each nest 12 includes a flange assembly for coupling the nest to the chain 13 and generally indicated by the reference numeral 80 (3, 21, 27). Each flange assembly 80 is resiliently mounted on its associated flange body 20 by means of a bolted connection employing resilient spacer washers 81 and 82 (21, 27). The horizontally sidewardly extending tabs 83 (21, 27) associated with the flange assembly 80 are provided with rubber blocks 84 (27) which are fixed therein and which have fixed thereto steel bushings 85. Each of the steel bushings 85 receives a steel pin 86 extending from the chain 13 and serving as a link pin for the chain and also as a coupling between the chain and the nest structure. It will thus be seen that

the nest is coupled to the pin by connections which are resilient in all directions. The resiliency of the coupling in the direction of the translation of the chain and nests is particularly important in the non-circular indexing table arrangement embodied in the structure shown in the drawings inasmuch as the spacing between centers along the chain changes slightly as the chain leaves a straight reach and engages the sprocket, and it again changes as the chain subsequently leaves the sprocket and enters a straight reach. Furthermore, the resilient connections in the several directions are important in order to accommodate the slight dimensional variations which inevitably occur in the construction of production machines which are many feet in length and have a number of moving parts. The linkage so far described is therefore relied on only to approximately locate the nests 12 at the several stations. Also provided are interengageable nest locating means associated with each nest and with each decorating station and with the centering station and adapted to interengage near the beginning of and disengage near the end of the dwell of each nest at each of such stations.

In the illustrated apparatus, these means comprise locating pins 90 (21, 23) located adjacent each of the decorating stations and the centering station. In the particular apparatus illustrated, the upper guide for the pins 90 is fixed to the sides of the outer channel rail 14. Each pair of pins 90 are actuated by a hydraulic cylinder 91 mounted beneath the main table plate 10 through a suitable yoke linkage, as clearly illustrated in the drawings. The nest bodies 20 have formed therein sockets 93 which are preferably provided with bushings, as shown, for reception of the locating pins 90.

Centering station

Details of the centering station or the station III, as shown in Figure 1, are most clearly seen in Figures 13-15. Provided at the centering station are a pair of centering chucks 95 and 96 (13-15) which are provided with vertical rollers 97 to minimize friction with the ware to be engaged. The ware chucks 95 and 96 are formed integrally with the racks 98 and 99 respectively, each of which slides in the keyway 100 (14). The racks 98 and 99 are engaged by a pinion 101 (14, 15) which is keyed to the same shaft as is a crank 102 (13, 14) which carries a spring-loaded pin 103 (14). Mounted below the crank is a drilled plate 104 which is integral with a pinion 105. The pinion 105 is engaged by a rack 106' which is controlled by an actuating cylinder 107 (13). The inward limit of the movement of the centering chucks 95 and 96 is changed by lifting the pin 103 and rotating the shaft 106 to effect the desired adjustment and then reinserting the pin 103 in a different one of the drilled passages in the plate 104. It will be seen that the linkage is such that the centering chucks move inwardly together toward the center of a nest positioned at the centering station with a uniform motion. The lines supplying the hydraulic cylinder 107 lead from a pressure reducer of a conventional type whereby ware engaged by the centering chucks 95 and 96 is not crushed even though such engagement occurs slightly before the actuating cylinder 107 reaches its limit of extension.

Vacuum distribution head

The various vacuum lines are supplied by the main vacuum line header 17 (32) which communicates with the interior of the vacuum distribution head located centrally of the indexing mechanism and generally indicated in Figure 1 by the reference numeral 110. This mechanism comprises a pair of reels 111 and 112. The reel 111 is rotatably mounted on the central hollow shaft 113 which is provided with a vacuum passage 114 which communicates with the main vacuum line header 17 as shown in Figure 32. Through a port 115 (32) and a manifold passage 116, which is rendered vacuum tight by suitable seals as shown, the vacuum passage 114 communicates with the line 117 which furnishes vacuum to

the rim of the reel 111 and to one of the vacuum lines 16 which is wound and unwound on the reel as shown in Fig. 33. The other reel 112 is keyed to the shaft 113 and communicates through the port 120 with a line 121 which furnishes vacuum to the rim of the reel 112 and to the remaining one of the vacuum lines 16 which leads from the vacuum distribution head. The shaft 113 and the reel 111 are pinned to opposite ends of a spring 123 (32) and when the lines 16 are unwound therefrom, the spring is tensioned in a direction to take up these lines and keep them from becoming fouled in the apparatus.

Apparatus for exchanging ware between conveyor and indexing mechanism

The apparatus for feeding the undecorated ware from the conveyor 11 to the indexing mechanism and for returning decorated ware to the conveyor 11 is illustrated in Figures 3-12.

In order to suitably space undecorated ware as it arrives at the ware decorating machine, there is provided an escapement mechanism in the form of a pair of gates or detaining fingers 130 (2, 5, 9) and 131 (2, 5). These members each depend from one of a pair of beam assemblies 134 which are mounted for bodily sliding movement in a suitable keyway, as indicated in Figure 10. The stationary housings around these members is indicated by the reference numeral 135 (2, 5, 9, 10). The beam assemblies 134 are each actuated by one of the hydraulic cylinders 136 (2, 5, 9).

The ware may be guided along the conveyor by suitable side guide rails 137 (1-5, 9) and may be held down to prevent overlapping by a top rail 138 (1-3, 5).

The beam assemblies 134 and the associated pairs of detents 130 and 131 are raised and lowered in alternating relationship to establish an escapement action and space the incoming ware in desired intervals to be subsequently received at a stop plate 139 (1, 2, 4, 6).

Extending between the conveyor 11 and the loading and unloading stations I and X is a traverse mechanism including a traverse beam 140 (1, 4, 7, 8). The foot structure 141 (7, 11) integrally associated with the traverse beam 140 is slidably received for vertical movement in a keyway 142 (11) associated with a fixed beam 143 (7, 11) and is actuated by a hydraulic cylinder 144 (2, 6, 7). Carried bodily on the foot structure 141 is a rack 145 (2, 6, 7) which is actuated by a hydraulic cylinder 146. The rack 145 engages a pinion 147 (6, 7, 11) which, through a sprocket 148, chain 149 (7), sprocket 150, and sprocket 151 (4, 6, 7), drives a chain 152 (4, 7, 8). The chain 152 is coupled to a sliding head assembly 153 (7, 8, 12) which slides in a keyway associated with the traverse beam 140 as most clearly seen in Figure 8. The sliding head assembly carries a pair of vacuum cup heads, each communicating with a vacuum line 155, one of the vacuum heads being shown in Figure 12. Each vacuum head includes a slideable hollow stem 156 (12) which is spring urged to an extended position and which has mounted a vacuum cup 157 at its lower end in a manner which will be clear from Figure 12. The line 155 leads from a source of vacuum through a suitable valve (not shown) adapted to alternatively apply vacuum to the vacuum cup and to port the vacuum cup to atmosphere. Such control valves are familiar to those with a knowledge of pneumatic apparatus.

The solenoids which actuate such control valves are controlled by the master timer so that vacuum is applied as the vacuum cup 157, associated with the loading station I is lowered into contact with a plate held against the stop plate 139. The timer control is such that this vacuum is maintained until the plate is lifted and translated from the conveyor 11 to the loading station I and then lowered onto a waiting nest. When the ware has been lowered on the nest, the vacuum control valve for

the associated vacuum cup 157 is reversed by the central timer to port the vacuum cup 157 to atmosphere and release vacuum.

An opposite sequence of operation occurs in the case of the vacuum cup associated with the unloading station X. In this case, the vacuum is applied while the vacuum cup 157 is positioned over a piece of ware supported on the nest at the unloading station X. The vacuum is maintained during subsequent lifting of the piece of the ware and its translation from the unloading station X to the conveyor 11 and during its lowering onto the conveyor 11. When the ware has been lowered onto the conveyor 11, the control valve for the vacuum cup 157 is reversed to vent the vacuum cup to atmosphere and release the ware.

The hydraulic cylinders 144 and 146 are actuated in proper sequence to accomplish the desired exchanges of ware between the conveyor and the loading and unloading stations. The cylinders 144 act to bodily lift the traverse beam 140 and its foot structure 141 together with all the elements supported thereon including the linkage powered by the hydraulic cylinders 146. This movement of the traverse beam 140 accomplishes the lifting and lowering of the ware pieces. The cylinders 146 are actuated to move the sliding head assembly 153 back and forth. This accomplishes the translation of the ware back and forth between the conveyor and the indexing mechanism. Each time the sliding head assembly 153 is translated from the conveyor 11 to the indexing mechanism, it carries with it a piece of ware to be deposited at the loading station I. Each time the sliding head assembly 153 is translated in the opposite direction, it carries with it a decorated piece of ware which it has picked up from the unloading station X.

Operation at the loading station I

Each nest 20 arrives at the loading station I with its associated vacuum valve 32 in the off position, the vacuum valve having been maintained in the off position by the cam bar 63 and being maintained in the off position as the nest comes to rest at the loading station by the fact that the actuating cylinder 61 is extended. The hydraulic cylinder 41 is then extended to raise the plunger 40 and thereby raise the nest vacuum cup 22. The ware piece held by the vacuum cup 157, associated with the traverse beam 140 and with the loading station, is then lowered by retraction of the hydraulic cylinder 144, and the ware is released from the vacuum valve 157 to be gently deposited on the vacuum cup 22. Vacuum is then applied to the cup 22 by retraction of the hydraulic cylinder 61 causing the cup 22 to tightly grip the underside of the ware. The cylinder 41 is then retracted to lower the ware into engagement with the ribs 23. The relationship of the parts is such that with no piece of ware on the nest, the vacuum cup 22 is located slightly below the level of the ribs 23 when it is in its retracted position. When the cup 22 is in gripping engagement with the underside of the ware, however, it is constrained, even in its retracted position, to remain in gripping relation with the ware due to its resilience. There is accordingly established a firm positioning of the ware on the nest. If desired, the ribs 23 can be made narrow and provided with sharp edges (not shown) to increase the strength of the grip and particularly to further assure against twisting of the ware with respect to the ware chuck elements.

It will be understood that in many aspects of the invention, the vacuum cup lifting and lowering feature is not essential, but it is here described in order to disclose what presently appears to be a highly advantageous detail of the apparatus, but one which is not essential to all aspects of the invention. The advantage in raising and lowering the vacuum cup at the loading station is that it enables the ware to be very gently lowered onto the face of the nest or onto the ribs 23. In this con-

nexion, it is desirable to provide for a suitably gentle actuation of the hydraulic cylinder 41. This can be accomplished by well-known expedients in hydraulic controls.

Operation at the centering station III

The ware is translated to the centering station with the vacuum on and the ware in tightly gripped relationship with its associated vacuum cup 22. As the nest arrives at the centering station, the associated centering pins 90 are raised to positively locate the nest in a very precise manner. The vacuum cup 22 is then raised by actuation of the associated cylinder 61 located at the centering station III. The vacuum in the vacuum cup is then broken by actuation of the hydraulic cylinder 41 associated with the centering station III. The centering chucks are then urged inwardly by actuation of the hydraulic cylinder 107 whereupon the ware is moved toward a central position. During or following this centering movement of the centering chucks 95 and 96, the vacuum cup 22 is lowered. The vacuum cup is then immediately raised and vacuum is applied to the cup, whereupon the cup is again lowered. Prior to the latter lowering of the vacuum cup 22, the ware chucks 95 and 96 are preferably disengaged from the ware so that the ware will not have to slide along the rollers 97 as it is lowered onto the nest face by retraction of the cup 22. The intermediate lowering and raising of the cup 22, while the vacuum is off and while the ware is being moved to or being held at the centering position, is desirable in order to prevent the possibility of the vacuum cup being slightly deformed by sliding contact with the ware as the ware is being centered. Such slight deformation of the vacuum cup might lead to an inaccurately centered piece of ware when the vacuum is subsequently applied to the cup 22 to hold the ware in its centered position. It will be seen that in this connection the raising and lowering of the vacuum cup 22 is highly advantageous although in many refined versions of the invention, it is possible to center the ware by dragging it over a vacuum applying element or other ware gripping means which is not capable of being raised or lowered. After the ware is established in its accurately centered and gripped relationship on the face of the nest, centering pins 90 are lowered prior to all indexing of the nest to the next station.

Operation at the unloading station X

After arrival of the nest at the unloading station, the cup 22 is raised by actuation of the cylinder 61 associated with the unloading station. Vacuum is turned off by actuation of the cylinder 41 associated with the unloading station. The ware is then picked off the vacuum cup 22 by the vacuum cup 157 carried on the sliding head assembly 153 and associated with the unloading station. The cup 22 is then lowered, and the nest is indexed to the loading station. The associated hydraulic cylinder 41 which controls vacuum at the unloading station is not retracted until the nest leaves the unloading station. The follower 58 associated with the nest is thereby maintained in raised position by the cam bar 63 so that the vacuum "off" condition for the nest is maintained during movement of the nest from the unloading station X to the loading station I.

Operation at the several decorating stations

The several decorating stations are located adjacent to bays formed by pairs of beams 160 (1) extending sideways from the indexing apparatus. These beams are adapted to support decorating units such as stamping units and spraying units which can be wheeled into position at the several decoration stations and lowered onto the beams 160 to be bolted thereto to be positively and accurately positioned at the several stations. To set up the machine for different decorating processes, it is possible to exchange the machines at the several stations

and arrange them in any desired order. For stamping operations, it is desirable to maintain the ware at the decorating station in a positively indexed position. For spraying operations, it is desired to rotate the ware at the decorating stations and to have the ware located at its positively indexed position following rotation. It is contemplated also that there may be other decorating operations where it is desirable to manipulate the ware in one of the above described manners at the decorating stations.

At decorating stations where the ware is to be rotated, the associated hydraulic cylinder 57 is actuated after reception of the nest at the station and raising of the associated locating pins 90 by the hydraulic cylinder 91. The gear 51 is thereby raised into engagement with the gear 24, the detent 64 being lifted out of engagement with the gear 24 by engagement of the face of the gear 51 with the roller 59. The hydraulic cylinder 46 is then actuated to cause a positive amount of rotation of the ware chuck 21. That the amount of this rotation is positive is assured by the positive displacement characteristics of the hydraulic actuating elements. After the cylinder 46 reaches its limit of travel, the cylinder 57 is actuated to allow the detent 64 to reengage the gear 24 and to disengage the gear 51 from the gear 24. The pins 90 are thereupon lowered and the nest indexes to the next station.

At decorating stations where the ware is to be held in indexed position without rotation, the indexing pins are raised to positively locate the ware shortly following its reception at the station and are lowered to allow subsequent translation of the nest following the decorating operations at that particular station. The engagement of the gear 51 associated with the station and the gear 24 associated with the nest and the actuation of the associated cylinder 46 is prevented by reversing switches, such as the switch 7 (50), associated with the electric lines from the master timer to the solenoid operated hydraulic valves associated with each of the hydraulic cylinders in question. This can, of course, be very simply accomplished as part of the programming of the machine for the particular run of ware to be decorated. It will thus be seen that there has been provided means associated with each decorating station for actuating the chuck-rotating drive linkage of each nest during its dwell at the decorating station, and means to selectively program such last named means for effecting such actuation of the chuck-rotating drive linkage of each nest only at one or more decorating stations which are chosen for a particular production run. Ware carried in the nests will remain at the datum rotative position during their dwell at decorating stations other than such chosen decorating stations.

It should be obvious from the above that ware being processed is accurately positioned and precisely defined at each of the several decorating stations in centered attitude and at a correctly indexed datum rotative position and is either rotated theretofrom and to such datum rotative position or is maintained in such datum rotative position according to whether or not the particular decorating station is one of the stations which has been chosen for chuck rotation.

Spray unit

The spray unit is illustrated in Figures 34-40. It is supported above a table 165 (34, 35, 38A) which forms part of a portable cart. The spray unit is raised by the elevating screws 166 (34, 35, 38, 38A) which are built into the supporting table 165 to the necessary height for placing the lower frame 167 (34, 35, 38) of the spray unit proper on the beams 160 (1) defining the bays adjacent the various decorating stations. The frames 167 are fastened by bolts to the beams 160 after registering pins 168 (35) are in place. The elevating screws may be ac-

tuated by a suitable linkage leading from a hand crank shaft 169 (34, 35).

Various parts of the spray unit are actuated by hydraulic cylinders which are controlled from the main timer in the same way as previously described in connection with the main indexing mechanism. The control set up for each of these cylinders is similar to that shown in Figure 50. The electrical leads for control of the spray unit at a given decorating station are established by 5 multiple-contact plug receptacles at each decorating station, including the particular decorating station (the contacts of these receptacles being connected in parallel), and by a mating multiple-contact plug associated with the spray unit. This is indicated schematically in Figure 50 by the broken line A—A, which represents a disconnectable plug to be provided when the hydraulic cylinder shown in Figure 50 is one of those associated with the spray unit or other removable decorating unit. Thus, it will be understood that in such a case the portion of 10 the circuit shown to the left of line A—A in Figure 50 is permanently associated with a given decorating station, while the portion shown to the right of line A—A in Figure 50 is permanently associated with a given spray unit. It will be clear, of course, that the disconnectable 15 plug represented by the line A—A may be disregarded when Figure 50 is taken as illustrating a typical control arrangement for parts associated with the main indexing mechanism rather than for parts associated with a decorating unit which is to be, perchance, shifted from one 20 decorating station to another.

The necessary hydraulic power supply unit is contained within the spray unit within the housing 170 (34, 35, 38A). The drive motor for the hydraulic pump mechanism is shown at 171 (34, 38A). The electrical leads 25 for powering the motor 171 lead through the multiple-contact plug connection, mentioned above. Solenoid valves associated with the spray unit and corresponding to valve 5 (50) are also contained within the housing 170.

It will be seen that in accordance with the above description, all power connections and timed electrically controlled operations are tied into the main indexing table and master control timer and can be made quickly and surely.

Each spray unit comprises a spray station which is generally indicated by the reference numeral 172 (34, 36, 38). The spray station 172 is positioned at the decorating stations of the bay in which the spray unit is temporarily mounted for the purposes of making a particular production run. The spray unit also comprises a cleaning station, generally indicated by the reference numeral 173 (35, 36), and a drying station, generally indicated by the reference numeral 174.

The spray unit proper includes three decoration-defining masks or templates 175 (35, 38), each of which is 35 associated with a carrying block 176 adapted to be magnetically held to or released from an electromagnet 177 (34, 35, 38) carried below the end of each of three arms 178, which, in turn, are carried on a column 179 which is capable of being bodily raised and lowered by the hydraulic cylinder 180 (34, 35, 38, 38A).

Each mask or template 175, together with its associated block 176, is provided with lower locating holes 181 (38). These receive locating pins at the cleaning station and drying station, as later described in greater detail.

Locating pins are positioned on the bottom of the electromagnets 177 and are received in locating holes 182 formed in the top of each block 176. This assures that each block 176, together with its associated mask 175, will be picked up by the electromagnet 177 in a position 40 which is in clearly indexed condition with regard to rotative position.

Each of the arms 178 is provided on its lower side with a socket sleeve 183 (34, 35, 38) and locating pin 184 is adapted to be received in each of these sleeves 183 as the 45 central column 179, together with the arms 178, is low-

ered by retraction of the hydraulic cylinder 180. The pin 184 is actuated by the hydraulic cylinder (not shown) located within the sleeve 185.

The central column 179 has keyed thereto a gear 183 (35-37, 39).

A sliding table comprised of a number of elements, each labeled 190 (34-40), is mounted for transverse motion for a small distance of the order of an inch or less from one side of the machine to the other, that is, between the top and the bottom of the drawing as the machine is viewed in Figures 36 and 37.

The sliding table 190 slides on a fixed keyway 191 (38, 40) and is guided and supported by rollers 192 (35-38) and rollers 193 (36-38). The rollers 193 are located on the upper side of the plate 190 due to the effect of the weight distribution of the elements associated with the plate 190. A keyway 194 (35-37, 39) forms part of the structure associated with the plate 190 and moves therewith. The plate 190 is reciprocated by a hydraulic cylinder 195 (35-37). An actuating cylinder 197 (36-38) is carried bodily on the plate 190. A reciprocating plate structure, generally indicated by the reference numeral 200 (34-40), is carried on the plate 190 and is engaged with the keyway 194. A slot 201 (36, 37) formed in this plate allows the plate to reciprocate in surrounding relationship to the column 179. Fixed to the plate 200 are a pair of racks 202 (35-37, 39, 40) and 203 (35-39). When the table 190 is in one extreme position, the rack 202 is engaged with the gear 188, as indicated in Figure 37, and when the table 190 is in its opposite position, the rack 203 is engaged with the gear 188. The associated cams on the master timer shaft 2 (50), which cams control the actuation of the cylinders 195 and 197, and the cylinder within the sleeve 185 are profiled so that, as the locking pin 184 is withdrawn, the cylinder 197 is actuated to advance the column 179 and the arms 178 by 120 degrees (at which stage the parts reach the position shown in Figure 37), and the pin 184 is then re-engaged, the actuating cylinder 195 meanwhile being energized to disengage the rack 202 and engage the rack 203 preparatory to a succeeding actuation of the cylinder 197 for further rotating the column 179 an additional 120 degrees. In this way, an intermediate advance of the arms 178 is accomplished with the parts being at all times positively mechanically locked in properly indexed position.

The cleaning station 173 comprises a tank 205 (35, 36) which may contain a cleaning solution, such as a solvent for the coating being applied to the ware. A rotating support 206 (36) is located within the open top receptacle 205 and is fixed to a shaft 207 (36, 37) which depends through a fluid type seal on the bottom of the receptacle 205 and is keyed to a gear 208 (37). The gear 208 is engaged with a pinion 209 which is fixed to the same shaft as a pinion 210 (36). A pinion 210 is engaged by a rack 211 which is actuated by a hydraulic cylinder 212 (35, 36). At the hub juncture of the shaft 207 and the rotating support 206 are provided locating pins 215 (36) which are adapted to be received in mating relationship in the locating holes 181 associated with each nest. A locating notch 216 is formed in the rim of the rotating support member 206.

The drying station is similar to the cleaning station and includes a receptacle 205A (34-36), a rotating support member 206A (35, 36), a shaft 207A (36, 37), a gear 208A (37), a gear 209A, a gear 210A (36), a rack 211A (36, 38), an actuating cylinder 212A (34-36, 38), locating pins 215A (36), and a notch 216A. It will be seen that the numerals just given are the same as the reference numerals applied to corresponding elements associated with the ware cleaning station, with the exception that the letter "A" has been added. Further description of these elements is believed unnecessary. Each of the notches 216 and 216A is engaged by a solenoid actuated detent wheel, one of which is associated

with each of the two stations, but only one of which can be seen in Figure 36. Reference numeral 217 is applied to this element.

A spray gun 218 (35) or other spray means is carried 5 on the cross arm 219 formed on the sleeve 185. The spray gun is controlled by a suitable solenoid valve (not shown) tied into the master timer shaft 2 through the previously mentioned disconnectable multiple-contact plug, in a manner which will be apparent.

10 *Operation of the spray unit*

As the apparatus approaches the end of a cycle, the cylinder 195 is actuated to shift one of the racks 202 or 203 into engagement with the gear 188 and prepare the 15 spray unit for indexing to the next rotative position of the arms 178 and associated elements. As the succeeding cycle begins, a nest 12 is indexed to the decorating station with which the spray unit is associated, and it is positioned accurately at the station by interengagement of the 20 locating pins 90, associated with the station, and the locating holes or sleeves 93, associated with the nest. Meanwhile, the cylinder 197 is actuated to index the arms 178 to the next position. The actuating cylinder 180 is then retracted to lower the main column 179. The electro- 25 magnets 177 are then de-energized to cause the several masks 175 to be deposited at the several stations. The mask 175 at the decorating station proper is deposited on the ware; the mask 175 at the cleaning station 173 is deposited in the cleaning solution and its proper rotative position is maintained by interengagement of the pins 215 30 with its associated locking holes 181. The remaining mask 175 is deposited at the drying station, its proper rotative position being similarly maintained. Directed toward the drying station, constantly or otherwise as desired, 35 may be a stream of heated air or similar drying arrangement.

The electromagnets 177 and the solenoids associated with the detent wheels 217 are controlled by being suitably tied into the master timer shaft 2 to be controlled by 40 cams associated therewith, such tying in being effected through the previously mentioned disconnectable multiple-contact plug in a manner which will be apparent.

After the masks 175 are deposited at the respective stations, the cylinder 180 is again actuated in the opposite 45 direction to raise the column 179. The timed relationship is such that the ware chuck on the nest is then rotated. During rotation, the spray gun 218 or equivalent means is actuated to coat the ware with a stenciled pattern or the like. Meanwhile, the members 217 are withdrawn and 50 the cylinders 212 and 212A are extended and retracted to cause each of the associated masks 175 to be rotated, first in one direction, and then in the other, the members 217 being urged inwardly within the last fraction of a turn of each of the masks 175. The cylinder 180 is then again 55 actuated to lower the column 179, and the electromagnets 177 are energized to pick up the respective blocks 176 and masks 175, and as the end of the cycle approaches, the cylinder 195 is actuated to reverse the engagement of the racks 202 and 203 preparatory to the next cycle.

60 The precisely centered condition of the parts over the ware nest itself and the considerable weight of the block 176, associated with the mask 175, makes it possible to maintain the correctly indexed rotational position of the mask 175 with sufficient accuracy during the actual spraying operation despite the fact that there is no positive engagement of any part of the mask assembly with any other positively indexed part through means such as the locating pins 215A. However, the provision of indexing means, such as the locating pins at the bottom of the 65 electromagnets, assures that there will not be any cumulative dislocating effect since each mask is again positively indexed as soon as it is re-engaged with one of the electromagnets 177. Positive indexing obtains, at all times, at the other two stations of the spray unit.

70 The actuating cylinder 212 may be actuated in one di-

rection incident to cleaning of a first nest at the station 173 and in the opposite direction incident to the cleaning of a subsequent nest at this station. Thus, the supporting members 206 and 206A may turn in one direction for one cleaning operation and one simultaneous drying operation and in another direction for the next succeeding cleaning and drying operations. To this end, the control for the actuating cylinders 23 may be by means of a follower 221 (50) engaging a cam 220, the follower 221 being equivalent to the follower 2A except that the follower 221 is actuated at half frequency with relation to the cycle of operation of the main indexing apparatus due to the fact that the cam 220 is mounted on a cam shaft 222 which is in driven engagement with the cam shaft 2 and rotates at half the speed of the cam shaft 2.

Each of the masks 175 may be located at the same station of the decorating unit for two successive cycles of the indexing machine. This may be particularly desirable for high speed operation where the coating is such that the masks are not fouled by double use and where it is not feasible to rotate the masks 175 in opposite directions at the cleaning and drying stations in one cycle, but where such reversal of rotation is, nevertheless, desired. Thus, the support members 206 and 206A may turn in one direction for one cleaning operation and one simultaneous drying operation and in another direction for the next succeeding cleaning and drying operation by an arrangement described above, and at the same time the control for the actuating cylinders 195 and 197 may be actuated in a reverse direction every other cycle so that it is actuated in a given direction only every fourth cycle. To this end, the control for these cylinders may be by means of a follower 225 (50) engaging a cam 226, the follower 225 being equivalent to the follower 2A except that the follower 225 is actuated at one fourth the frequency with relation to the cycle of operation of the main indexing apparatus due to the fact that the cam 226 is mounted on a cam shaft 227 which is in driven engagement with the cam shaft 2 and which rotates at one fourth of the speed of the cam shaft 2.

Of course, the same effects as those described above may be achieved by driving the master timer at half the cycle speed of the main indexing unit or at one fourth the cycle speed and appropriately duplicating the cam profiles around the circumference of each cam, except for those cams where the frequency of operation is to be less than that of the cycle of operation of the main indexing apparatus.

Stamp unit

The stamp unit is illustrated in Figures 41-49. It is supported above the table 235 (41, 42A, 43A) which forms part of a portable cart. The stamp unit is raised by the elevating screws 236 which are built into the support table 235 to the necessary height for placing the lower frame 237 of the stamp unit proper on the beams 160 (1) defining the bays adjacent the various decorating stations. The frames 237 are fastened by bolts to the beams 160 after registering pins 238 (42A) are in place. The elevating screws may be actuated by a suitable linkage leading from a hand crank shaft 239 (41, 43A).

Various parts of the stamp unit are actuated by hydraulic cylinders which are controlled from the main timer in the same way as previously described in connection with the main indexing mechanism and the spray unit. The control set up for each of these cylinders is similar to that shown in Figure 50. The electrical leads which control the stamp unit at a given decorating station are established by multiple-contact plug receptacles at each decorating station, including the particular decorating station (the contacts of these receptacles being connected in parallel), and by a mating multiple-contact plug associated with the stamp unit. Again, the illustration in Figure 50 serves as a schematic showing of such control means, the disconnectable multiple-contact plug

connection being indicated by the line A—A when the hydraulic cylinders shown in Figure 50 are taken as being one of those associated with a removable decorating unit, such as the stamp unit.

5 The necessary hydraulic power supply unit is tied within the stamp unit within the housing 240 (41, 42A, 43A). The drive motor for the hydraulic pump mechanism is shown at 241. The electrical leads for powering the motor 241 lead through the multiple-contact plug connection, mentioned above. Solenoid valves associated with the stamp unit and corresponding to the valve 5 (50) are also contained within the housing 240.

10 It will be seen that in accordance with the above description, all power connections and timed electrically controlled operations are tied into the main indexing table and master control timer and can be made quickly and surely.

15 The stamp unit comprises a ram assembly, generally indicated by the reference numeral 248 (41, 42), and a platen and inking assembly, generally indicated by the reference numeral 249. It will be understood that both these assemblies are supported in association with the same general frame structure, which has open access ports 247 (41, 42, 44, 47). The platen is indicated by 20 the reference numeral 250 (42, 43, 45). It is moved back and forth from the rear end of the machine at which it is most remote from the decorating station to the front of the machine where it is positioned directly at the decorating station and under the ram. The platen 25 is powered by a drive cylinder 251 (42A, 43A, 48) through a linkage comprising a rack 252, a pinion 253, a gear 254, a pinion 255 (42A, 48), a sprocket 256 (42A, 43A, 48), a chain 257 (42A, 43, 43A, 45, 48), a sprocket 258 (43, 45), sprockets 259 (42, 43, 45, 46) and chains 30 260 (42, 44, 45, 46). The chains 260 engage the side extensions 261 (43, 45, 46) of the platen carriage. These extensions also carry rollers 262 which are guided in channel tracks 263 (42, 43, 45, 46). The platen table proper is rotatable on the platen carriage, being associated therewith by means of a friction pivot mount 264 (42, 45). The rim of the platen has a ratchet 265 (43, 45) which is adapted to be engaged by a fixed finger 266 (43, 45) associated with the frame upon each return of the platen to its starting position most remote from the 35 nest. This indexes the rotation of the platen slightly to aid in evenness of distribution of ink on the platen and to promote evenness of wear.

40 The inking is accomplished from a known type of fountain and inking arrangement which, in the apparatus 45 illustrated, is actuated by a fountain drive cylinder 270 (41-44) through a linkage including a rack 271 (41-43), a pinion 272 (44), a gear 273 (41-44, 46), a pinion 274 (42, 43, 46) and a rack 275 (43, 46). A pin 276 projects from the side of the rack 275 and engages in a slot in a 50 fountain ratchet arm 277 (42, 43, 46). The ratchet arm swings on the same center as the fountain roll axis and carries a ratchet 278 (42, 43) which is adapted to engage the ratchet wheel 282 for driving the fountain roll. In a manner to be described, the ratchet arm also engages a 55 member carrying an ink transfer roll 279 (42, 46) and actuates it to shift it from engagement with a lower fountain roll 281 (42, 46) to the first of a series of four applicator rolls 280 (42, 45, 46). The arm carries the roll 279 which has formed thereon a projection 289 (42) 60 which is in following engagement with a lug 284 on the reverse side of the fountain ratchet arm 277 as it is viewed in Figure 42. Following engagement is maintained by the spring (not seen) which surrounds the shaft on which the arm mounting the roll 279 is pivoted 65 and which urges the arm in the appropriate direction to maintain following engagement.

70 The ram structure includes a printing head 291 (41, 42) which carries on its lower side a stamp. The stamp comprises a relatively thin elastomeric diaphragm 292 (42) forming the stamp proper and a pair of resilient and

spongy elastomeric layers overlying this stamp proper 292, the first of these layers being indicated by the reference numeral 293 and being relatively thin and the second of these layers being indicated by the reference numeral 294 and being relatively thick, the second elastomeric material 294 being more readily compressible than the first elastomeric material. By this means, the stamp is enabled to conform to the shapes of the ware to be printed with minimum smudging despite slight variations in the shape and attitude of the ware as it is held in ware nests passing the particular decorating stations with which the stamp unit is associated. In this connection, it has been found particularly desirable to provide an annular open centered stamp as shown. The ram head above the stamp proper comprises a pair of slideways which are normal to each other whereby the stamp may be exactly centered, centering in one direction being accomplished by adjustment of the set screws 295 (42, 44) and in the other direction being accomplished by adjustment of set screws 296.

The outer housing immediately in the vicinity of the ram actuating structure is indicated in Figures 42, 44, 47 and 49 by the reference numeral 297. The housing is reinforced by an inner heavily machined I-beam indicated by the reference numeral 298 (44, 49). Plates or bars 299 (44, 49) are bolted to one side of the member 298 to define a dovetail slot which receives the main sliding casting which guides the ram in its vertical movement. This casting is indicated by the reference numeral 300 (42, 44, 49). This casting has formed therein a vertical slot 301 (42, 47, 49). Positioned on the opposite side of the member 298 in the upper portion of the structure is a casting 305 (47, 49) which carries an actuating cylinder 310 (42, 44, 49). This cylinder actuates a pin 311 (47, 49) which can be extended through a vertical slot in the member 298 and into the vertical slot 301 by actuation of the cylinder 310. When the pin 311 is extended, it limits the distance of movement of the ram by engaging the upper end of the slot 301. This defines the platen-contracting position of the ram. When the pin is withdrawn, the ram is enabled to make a longer stroke to engage the ware in stamping relation. The lowermost position of the ram is defined by adjustment of a turnbuckle connection 313 (42) by the ram actuating cylinder 314 and the ram head.

The casting 305 is received in a dovetail slot defined by bars or plates 316 (47, 49) on one side, which are similar to the bars or plates 299, and the bars 317 which are slotted at 318. The slots 318 are adapted to slide over the bolts which retain the members 317. The member 317 is urged into wedging relationship with the casting 305 by gib locks 319 which are threadedly received in the casing 297. When it is desired to adjust the stop position for the short stroke or the platen-engaging stroke of the ram, a linkage is employed consisting of the wheel 321, main bevel gears 322 and 323 and an elevating screw 324, which is in operative association with the casting 305, the gib locks 319 are released, the wheel is turned to adjust the stop to the desired position, and the gib locks are again tightened. It will be clear that when the main ram cylinder 314 is extended, the ram will drop all the way down if the stop cylinder 310 is retracted and will drop only down to platen-engaging position if the cylinder 310 is extended.

An additional cylinder 325 (42) is provided to actuate a stop pin adapted to engage in a hole 326 when the ram is in its fully raised position. The cylinder 325 is spring-loaded to be normally extended and it is retracted whenever there is hydraulic pressure in the hydraulic system associated with the stamp unit. This merely assures that the ram will be locked in up position when the apparatus is shut down or when the stamping unit is disassociated from the main indexing apparatus for repair or storage.

Operation of the stamp unit

When the apparatus is started up and hydraulic pressure built up, the actuating cylinder 325 is retracted against the pressure of the spring which normally urges it into extended position. The associated pin is thereby withdrawn from the hole 326, unlocking the ram from its raised position. This unlocked condition obtains all during the operation of the ram and until such time as the apparatus is again shut down and hydraulic pressure forms, at which time the associated pin is again engaged in the hole 326, locking the ram in its raised position.

At the early part of each operative cycle of the main indexing mechanism, the actuating cylinder 251 completes a stroke to position the platen or ink desk 250 over the ram, and the ram actuating cylinder 314 is then actuated to lower the ram, the ink stop cylinder 310 meanwhile having been actuated to limit the downward movement of the ram by engagement of the pin 311 with the top end of the long slot 301. At the limiting position thus defined, the stamp 292 just engages the inked platen to be evenly inked without smudging or ridging of the ink on the ridges or other decoration-defining or indicia-defining high spots of the stamp. The ram actuating cylinder 314 is then reversed or retracted to raise the ram, and the locking pin actuating cylinder 310 is also retracted. The actuating cylinder 251 is also reversed to translate the platen toward the rear of the machine and under the inking rolls 280. Meanwhile, at about the same time, the cylinder 270 is actuated to shift the top of the fountain ratchet arm 277 to the right as it is viewed in Figure 42. This indexes the main fountain roll, seen in Figure 46, and meters a measure of ink onto the secondary fountain roll 281 and also brings the roll 279 in contact with the secondary fountain roll 281 due to the spring-loading of the arm carrying the roll 279. About the time the platen reaches its rearmost position, the fountain actuating cylinder 270 is reversed. It carries the pawl 278 on its return stroke without further motion of the fountain rolls and also, through interengagement of the lug 284 with the projection on the carrying arm for the ink transfer roll 279, causes the ink transfer roll 279 to be transferred to the first of the rearmost inking rolls to remain in contact therewith.

When the platen again moves forward to contact the ink rolls, the ink transfer roll 279 will be briefly rotated by its frictional engagement with the first ink roll to transfer an additional measure of ink. These inking arrangements will be familiar to those with a knowledge of printing presses and are described here merely to clarify the mode of their incorporation with the apparatus. Meanwhile, in the given cycle being described, the ram actuating cylinder 314 is again extended to lower the ram, and the full lowering of the ram is accomplished at about the same time in the cycle that the ink transfer roll starts from the secondary fountain roll 281 to the first inking roll 280. A piece of ware is held on a nest at the decorating station with which the stamp is associated. The ware is held stationary during its entire dwell at the station due to pre-selection of the stationary characteristic which has been accomplished by reversing a switch or switches, such as the switch 7, from the position indicated in Figure 50 to accomplish the desired purpose as previously described herein. The stamp 292 engages the ware in printing contact. The action of the resilient foundation portions 293 and 294, the resiliency of which varies as described above, allows the stamp to conform to the gently tapering rim portion of the ware or to conform to other surfaces which are not precisely in a horizontal plane. The motion is actually preferably such that the ram continues to move a slight distance after initial contact of the stamp 292 with the ware, the resilient back-up layers insuring good contact between the stencil and the ware while, at the same time, avoiding smudging. The ram actuating cylinder

der 314 is again reversed causing the ram to be raised and the ware piece, together with its associated nest, is indexed to the next station on the main indexing apparatus to complete the cycle.

At the beginning of the succeeding cycle, the platen 250 again completes its forward stroke to a position over the ram and in the process of doing so passes in contact with the rolls 280, the first of which is in contact with the ink transfer roll 279.

The scope of the invention is not limited to the practice of all the structural and operative details mentioned above. These have been given merely by way of an example of a presently preferred embodiment of the invention.

What is claimed is:

1. Ware decorating apparatus for applying desired combinations of decorations which may be programmed in any desired order for any particular run of ware comprising a plurality of workpiece-supporting nests, linkage means for linking the nests together in a closed loop, drive means engaging the closed loop for successively intermittently advancing the nests to successive dwells at a loading station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck locating pin sockets in each nest body, locating pins at each decorating station, and control means for extending them near the beginning of said dwells and retracting them near the end of said dwells, means for centering the ware on the nests prior to reception of the ware at the decorating stations, a plurality of ware decorating units interchangeably mountable at each of the decorating stations, means associated with each of the decorating stations for activating the controlled operation of any decorating unit attached thereto in timed relationship to the intermittent advance of the closed loop of nests, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations whereby ware being processed is positioned, at each of the several decorating stations, in centered attitude and is either rotated thereat from and to a defined datum rotative position or is maintained in said datum rotative position according to whether or not the particular decorating station is one of the chosen stations.

2. Decorating apparatus for applying to ceramic ware decorations in desired combinations which may be programmed as desired for any particular run of ware comprising a plurality of nests for supporting workpieces, linkage means for linking the nests together in a closed loop, drive means engaging the closed loop for successively intermittently advancing the nests to successive dwells at a loading station, a centering station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, locating pin sockets in each nest body, locating pins at

each of said decorating stations and at said centering station and control means for extending them into said locating pin sockets at the beginning of said dwells and retracting them at the end of said dwells, means associated with the centering station for deactivating the ware gripping means associated with each nest toward the beginning of its dwell at said centering station and for reactivating said ware gripping means toward the end of said dwell, ware engaging members on opposite sides of the centering station and means moving them uniformly toward the center of said centering station into engaging relationship with ware positioned at said centering station between said deactivation and reactivation at said centering station of the ware gripping means associated with each nest whereby the ware is accurately centered on its nest and is then held in such centered condition, a plurality of ware decorating units, including spraying units and stamping units, interchangeably mountable at each of the decorating stations, means associated with each of the decorating stations for activating the controlled operation of any decorating unit attached thereto in timed relationship to the intermittent advance of the closed loop of nests, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations whereby ware being processed is positioned, at each of the several decorating stations, in centered attitude and is either rotated thereat from and to a defined datum rotative position or is maintained in said datum rotative position according to whether or not the particular decorating station is one of the chosen stations.

3. Ware decorating apparatus for applying desired combinations of decorations which may be programmed in any desired order for any particular run of ware comprising a plurality of workpiece-supporting nests, linkage means for linking the nests together in a closed loop, drive means engaging the closed loop for successively intermittently advancing the nests to successive dwells at a loading station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, interengageable nest locating means associated with each nest and with each decorating station and interengaging near the beginning of and disengaging near the end of said dwells and remaining disengaged between said dwells, means for centering the ware on the nests prior to reception of the ware at the decorating stations, a plurality of ware decorating units interchangeably mountable at each of the decorating stations, means associated with each of the decorating stations for activating the controlled operation of any decorating unit attached thereto in timed relationship to the intermittent advance of the closed loop of nests, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations whereby ware being processed is positioned, at each of the several decorating stations, in

centered attitude and is either rotated thereat from and to a defined datum rotative position or is maintained in said datum rotative position according to whether or not the particular decorating station is one of the chosen stations.

4. Decorating apparatus for applying to ceramic ware decorations in desired combinations which may be programmed as desired for any particular run of ware comprising a plurality of nests for supporting workpieces, linkage means for linking the nests together in a closed loop, drive means engaging the closed loop for successively intermittently advancing the nests to successive dwells at a loading station, a centering station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, interengageable nest locating means associated with each nest and with each of said decorating stations and said centering station and interengaging near the beginning of and disengaging near the end of said dwells and remaining disengaged between said dwells, means associated with the centering station for deactivating the ware gripping means associated with each nest toward the beginning of its dwell at said centering station and for reactivating said ware gripping means toward the end of said dwell, ware engaging members on opposite sides of the centering station and means moving them uniformly toward the center of said centering station into engaging relationship with ware positioned at said centering station between said deactivation and reactivation at said centering station of the ware gripping means associated with each nest whereby the ware is accurately centered on its nest and is then held in such centered condition, a plurality of ware decorating units, including spraying units and stamping units, interchangeably mountable at each of the decorating stations, means associated with each of the decorating stations for activating the controlled operation of any decorating unit attached thereto in timed relationship to the intermittent advance of the closed loop of nests, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations whereby ware being processed is positioned, at each of the several decorating stations, in centered attitude and is either rotated thereat from and to a defined datum rotative position or is maintained in said datum rotative position according to whether or not the particular decorating station is one of the chosen stations.

5. Ware decorating apparatus for applying desired combinations of decorations which may be programmed in any desired order for any particular run of ware comprising a plurality of workpiece-supporting nests, linkage means for linking the nests together in a closed loop, drive means engaging the closed loop for successively intermittently advancing the nests to successive dwells at a loading station, a centering station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation

of the chuck, interengageable nest locating means associated with each nest and with each of said decorating stations and said centering station and interengaging near the beginning of and disengaging near the end of said dwells and remaining disengaged between said dwells, means associated with the centering station for deactivating the ware gripping means associated with each nest toward the beginning of its dwell at said centering station and for reactivating said ware gripping means toward the end of said dwell, ware engaging members on opposite sides of the centering station and means moving them uniformly toward the center of said centering station into engaging relationship with ware positioned at said centering station between said deactivation and reactivation at said centering station of the ware gripping means associated with each nest whereby the ware is accurately centered on its nest and is then held in such centered condition, a plurality of ware decorating units, including spraying units and stamping units, interchangeably mountable at each of the decorating stations, means associated with each of the decorating stations for activating the controlled operation of any decorating unit attached thereto in timed relationship to the intermittent advance of the closed loop of nests, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations each of said spraying units being appropriate for association with one of said chosen decorating stations and comprising a plurality of spraying unit stations including a spray station which is positioned at the associated decorating station and a cleaning station and a drying station, three decoration-defining masks, means for laying each decoration-defining mask received at said spraying station on passing ware after the dwell of the ware at the associated decorating station is initiated but before its associated chuck-rotating drive linkage is activated, for spraying a coating on the ware during activation of such associated chuck-rotating drive linkage, and for picking up the particular mask after termination of the activation of such associated chuck-rotating drive linkage but prior of the termination of the dwell, means for immersing each decoration-defining mask received at said cleaning station in a solvent, means for spin-drying each decoration-defining mask received at said drying station, and means for successively intermittently advancing the masks to the spraying station, cleaning station and drying station in timed relationship with the intermittent advance of the closed loop of nests, each of said stamping units being appropriate for association with a decorating station other than one of said chosen stations and comprising a stamp, means for impressing said stamp on passing ware during dwell of the ware at the associated decorating station, and means for inking the stamp between such impressions.

6. Ware decorating apparatus for applying desired combination of decorations which may be programmed in any desired order for any particular run of ware comprising a plurality of workpiece-supporting nests, linkage means for linking the nests together in a closed loop, drive means engaging the closed loop for successively intermittently advancing the nests to successive dwells at a loading station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation

by said chuck is maintained in datum rotative position prior to and following rotation of the chuck, locating pin sockets in each nest body, locating pins at each decorating station, and control means for extending them near the beginning of said dwells and retracting them near the end of said dwells, means for centering the ware on the nests prior to reception of the ware at the decorating stations, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations whereby ware being processed is positioned, at each of the several decorating stations, in centered attitude and is either rotated thereat from and to a defined datum rotative position or is maintained in said datum rotative position according to whether or not the particular decorating station is one of the chosen stations.

7. Ware decorating apparatus comprising a plurality of workpiece-supporting nests, linkage means for linking the nests together in a closed loop, drive means engaging the closed loop for successively intermittently advancing the nests to successive dwells at a loading station, decorating stations and an unloading station, each nest comprising a nest body, a rotatable ware chuck carried by the nest body and including ware gripping means, and a drive linkage for rotating the chuck during dwell at at least one decorating station, interengageable nest locating means associated with each nest and with each decorating station and interengaging near the beginning of and disengaging near the end of said dwells and remaining disengaged between said dwells, means for centering the ware on the nests prior to reception of the ware at the decorating stations, at least one ware decorating unit mounted at said at least one of the decorating stations, means associated with said at least one decorating station for activating the controlled operation of said ware decorating unit in timed relationship to the intermittent advance of the closed loop of nests, said ware decorating unit constituting a spray station which is positioned at said at least one decorating station, a cleaning station and a drying station arranged around a circle, a column in the center of said circle, arms radially projecting from said column each with its outer end positioned over one of said stations, a decoration-defining mask at the end of each arm and releasably and reengageably held thereto by a magnetic coupling, means for intermittently rotating said column to advance said arms and said masks from said spray station to said cleaning station, from said cleaning station to said drying station and from said drying station back to said spray station in endless succession, means to momentarily lower said column and release said magnetic couplings following each advance and to then again momentarily lower said column and reactivate said magnetic couplings just prior to the next-succeeding advance, the release of the masks occurring during dwell of ware at said spray station whereby ware is presented for receiving each mask released thereat, means for spray-coating said ware while it is covered with a mask, means at said cleaning station for containing a solvent for the spray coating for receiving and cleaning each mask released thereat, and means at said drying station for receiving and collecting solvent run-off from each mask released thereat.

8. Ware decorating apparatus including ware advancing and indexing means and a ware decorating unit to which ware is to be presented by said means during a temporary dwell, said ware decorating unit constituting a spraying unit including a spray station, a cleaning sta-

tion and a drying station arranged around a circle, a column in the center of said circle, arms radially projecting from said column each with its outer end positioned over one of said stations, a decoration-defining mask at the end of each arm and releasably and re-engageably held thereto by a magnetic coupling, means for intermittently rotating said column to advance said arms and said masks from said spray station to said cleaning station, from said cleaning station to said drying station and from said drying station back to said spray station in endless succession, means to momentarily lower said column and release said magnetic couplings following each advance and to then again momentarily lower said column and reactivate said magnetic couplings just prior to the next-succeeding advance, the release of the masks occurring during dwell of ware at said spray station whereby ware is presented for receiving each mask released thereat, means for spray-coating said ware while it is covered with a mask, means at said cleaning station for containing a solvent for the spray coating for receiving and cleaning each mask released thereat, and means at said drying station for receiving and collecting solvent run-off from each mask released thereat, each of said last two named means including its own means for rotating mask-contacted elements associated with it during reception of each mask whereby cleaning is promoted by solvent agitation at the cleaning station without excessive splashing and spin drying occurs at the drying station.

9. Ware decorating apparatus for applying desired combinations of decorations which may be programmed in any desired order for any particular run of ware comprising a plurality of workpiece-supporting nests, linkage means for linking the nests together in a closed loop, drive means engaging the closed loop for successively intermittently advancing the nests to successive dwells at a loading station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, interengageable nest locating means associated with each nest and with each decorating station and interengaging near the beginning of and disengaging near the end of said dwells and remaining disengaged between said dwells, means for centering the ware on the nests prior to reception of the ware at the decorating stations, a plurality of ware decorating units, including spraying units and stamping units, interchangeable mountable at each of the decorating stations, means associated with each of the decorating stations for activating the controlled operation of any decorating unit attached thereto in timed relationship to the intermittent advance of the closed loop of nests, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations each of said spraying units being appropriate for association with one of said chosen decorating stations and comprising at least one decoration-defining mask, means for laying said mask on passing ware after the dwell of the ware at the associated decorating station is initiated but before its associated chuck-rotating drive linkage is activated, for spray-coating a coating on the ware during activation of such associated chuck-rotating drive linkage, and for picking up

said mask after termination of the activation of such associated chuck-rotating drive linkage but prior to the termination of the dwell.

10. Ware decorating apparatus for applying desired combinations of decorations which may be programmed in any desired order for any particular run of ware comprising a plurality of workpiece-supporting nests, linkage means for linking the nests together in a closed loop, drive means engaging the closed loop for successively intermittently advancing the nests to successive dwells at a loading station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, interengageable nest locating means associated with each nest and with each decorating station and interengaging near the beginning of and disengaging near the end of said dwells and remaining disengaged between said dwells, means for centering the ware on the nests prior to reception of the ware at the decorating stations, a plurality of ware decorating units, including spraying units and stamping units, interchangeably mountable at each of the decorating stations, means associated with each of the decorating stations for activating the controlled operation of any decorating unit attached thereto in timed relationship to the intermittent advance of the closed loop of nests, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations each of said spraying units being appropriate for association with one of said chosen decorating stations and comprising a plurality of spraying unit stations including a spray station which is positioned at the associated decorating station and a cleaning station and a drying station, three decoration-defining masks, means for laying each decoration-defining mask received at said spraying station on passing ware after the dwell of the ware at the associated decorating station is initiated but before its associated chuck-rotating drive linkage is activated, for spraying a coating on the ware during activation of such associated chuck-rotating drive linkage, and for picking up the particular mask after termination of the activation of such associated chuck-rotating drive linkage but prior to the termination of the dwell, means for immersing each decoration-defining mask received at said cleaning station in a solvent, means for spin-drying each decoration-defining mask received at said drying station, and means for successively intermittently advancing the masks to the spraying station, cleaning station and drying station in timed relationship with the intermittent advance of the closed loop of nests.

11. Ware decorating apparatus comprising a plurality of workpiece-supporting nests, linkage means for linking the nests together in a closed loop, drive means engaging the closed loop for successively intermittently advancing the nests to successive dwells at a loading station, decorating stations and an unloading station, each nest comprising a nest body, a ware chuck carried by the nest body and including ware gripping means, interengageable nest locating means associated with each nest and with each decorating station and interengaging near the beginning of and disengaging near the end of said dwells and

remaining disengaged between said dwells, means for centering the ware on the nests prior to reception of the ware at the decorating stations, at least one ware decorating unit mounted at said at least one of the decorating stations, means associated with said at least one decorating station for activating the controlled operation of said ware decorating unit in timed relationship to the intermittent advance of the closed loop of nests, said ware decorating unit constituting a stamping unit comprising a downwardly facing stamp underlain by a first relatively thin elastomeric material backed by a base of a second relatively thick elastomeric material, said second elastomeric material being more readily compressed than said first elastomeric material whereby said stamp conforms to the surface of ware to be printed with minimized smudging despite slight variances in the shape and attitude of said ware, means for impressing said stamp on ware during dwell of the ware thereunder, and means for inking the stamp between such impressions, said last named means comprising a platen, means to maintain the platen coated with ink, means for placing the platen under said stamp and for then touching the stamp against the platen and removing the platen all between said impressions whereby said stamp is subjected only to simple vertical translation during both inking and stamping to further minimize smudging.

12. Ware decorating apparatus for applying desired combinations of decorations which may be programmed in any desired order for any particular run of ware comprising a plurality of workpiece-supporting nests, linkage means for linking the nests together in a closed loop, drive means engaging the closed loop for successively intermittently advancing the nests to successive dwells at a loading station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, interengageable nest locating means associated with each nest and with each decorating station and interengaging near the beginning of and disengaging near the end of said dwells and remaining disengaged between said dwells, means for centering the ware on the nests prior to reception of the ware at the decorating stations, a plurality of ware decorating units, including spraying units and stamping units, interchangeably mountable at each of the decorating stations, means associated with each of the decorating stations for activating the controlled operation of any decorating unit attached thereto in timed relationship to the intermittent advance of the closed loop of nests, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations each of said stamping units being appropriate for association with a decorating station other than one of said chosen stations and comprising a stamp, means for impressing said stamp on passing ware during dwell of the ware at the associated decorating station, and means for inking the stamp between such impressions.

13. Ware decorating apparatus comprising a plurality of workpiece-supporting nests, linkage means for linking the nests together in a closed loop, drive means engaging the closed loop for successively intermittently advancing the nests to successive dwells at a loading sta-

tion, decorating stations and an unloading station, each nest comprising a nest body, a rotatable ware chuck carried by the nest body and including ware gripping means, and a drive linkage for rotating the chuck during dwell at at least one decorating station, interengageable nest locating means associated with each nest and with each decorating station and interengaging near the beginning of and disengaging near the end of said dwells and remaining disengaged between said dwells, means for centering the ware on the nests prior to reception of the ware at the decorating stations, at least one ware decorating unit mounted at said at least one of the decorating stations, means associated with said at least one decorating station for activating the controlled operation of said ware decorating unit in timed relationship to the intermittent advance of the closed loops of nests, said ware decorating unit constituting a spray station which is positioned at said at least one decorating station, a cleaning station and a drying station arranged around a circle, a column in the center of said circle, arms radially projecting from said column each with its outer end positioned over one of said stations, a decoration-defining mask at the end of each arm and releasably and re-engageably held thereto by a magnetic coupling, means for intermittently rotating said column to advance said arms and said masks from said spray station to said cleaning station, from said cleaning station to said drying station and from said drying station back to said spray station in endless succession, means to momentarily lower said column and release said magnetic couplings following each advance and to then again momentarily lower said column and reactivate said magnetic couplings just prior to the next-succeeding advance, the release of the masks occurring during dwell of ware at said spray station whereby ware is presented for receiving each mask released thereat, means for spray-coating said ware while it is covered with a mask, means at said cleaning station for containing a solvent for the spray coating for receiving and cleaning each mask released thereat, and means at said drying station for receiving and collecting solvent run-off from each mask released thereat.

14. Ware decorating apparatus comprising a plurality of workpiece-supporting nests, linkage means for linking the nests together in a closed loop, drive means engaging the closed loop for successively intermittently advancing the nests to successive dwells at a loading stations, decorating stations and an unloading station, each nest comprising a nest body, a ware chuck carried by the nest body and including ware gripping means, interengageable nest locating means associated with each nest and with each decorating station and interengaging near the beginning of and disengaging near the end of said dwells and remaining disengaged between said dwells, means for centering the ware on the nests prior to reception of the ware at the decorating stations, at least one ware decorating unit mounted at said at least one of the decorating stations, means associated with said at least one decorating station for activating the controlled operation of said ware decorating unit in timed relationship to the intermittent advance of the closed loop of nests, said ware decorating unit constituting a stamping unit comprising a downwardly facing stamp underlain by a first relatively thin elastomeric material backed by a base of a second relatively thick elastomeric material, said second elastomeric material being more readily compressed than said first elastomeric material whereby said stamp conforms to the surface of ware to be printed with minimized smudging despite slight variances in the shape and attitude of said ware, means

for impressing said stamp on ware during dwell of the ware thereunder, and means for inking the stamp between such impressions.

15. Ware decorating apparatus including ware advancing and indexing means and a ware decorating unit to which ware is to be presented by said means during a temporary dwell, said ware decorating unit constituting a spraying unit including a spray station, a cleaning station and a drying station arranged around a circle, a column in the center of said circle, arms radially projecting from said column each with its outer end positioned over one of said stations, a decoration-defining mask at the end of each arm and releasably and re-engageably held thereto by a magnetic coupling, means for intermittently rotating said column to advance said arms and said masks from said spray station to said cleaning station, from said cleaning station to said drying station and from said drying station back to said spray station in endless succession, means to momentarily lower said column and release said magnetic couplings following each advance and to then again momentarily lower said column and reactivate said magnetic couplings just prior to the next-succeeding advance, the release of the masks occurring during dwell of ware at said spray station whereby ware is presented for receiving each mask released thereat, means for spray-coating said ware while it is covered with a mask, means at said cleaning station for containing a solvent for the spray coating for receiving and cleaning each mask released thereat, and means at said drying station for receiving and collecting solvent run-off from each mask released thereat.

16. Ware decorating apparatus for applying desired combinations of decorations which may be programmed in any desired order for any particular run of ware comprising a plurality of workpiece-supporting nests, linkage means for linking the nests together in a closed loop, drive means engaging the closed loop for successively intermittently advancing the nests to successive dwells at a loading station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, interengageable nest locating means associated with each nest and with each decorating station and interengaging near the beginning of and disengaging near the end of said dwells and remaining disengaged between said dwells.

17. Ware decorating apparatus for applying desired combinations of decorations which may be programmed in any desired order for any particular run of ware comprising a plurality of workpiece-supporting nests, linkage means for linking the nests together in a closed loop, drive means engaging the closed loop for successively intermittently advancing the nests to successive dwells at a loading station, a centering station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, interengageable nest locating means associated with each nest and with each of said decorating stations and said centering station and interengaging near the beginning of and disengaging near the end of said dwells and remaining disengaged between said dwells, means associated with the centering station for deactivating the ware gripping means associated with

each nest toward the beginning of its dwell at said centering station and for reactivating said ware gripping means toward the end of said dwell, ware engaging members on opposite sides of the centering station and means moving them uniformly toward the center of said centering station into engaging relationship with ware positioned at said centering station between said deactivation and reactivation at said centering station of the ware gripping means associated with each nest whereby the ware is accurately centered on its nest and is then held in such centered condition, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations whereby ware being processed is positioned, at each of the several decorating stations, in centered attitude and is either rotated thereat from and to a defined datum rotative position or is maintained in said datum rotative position according to whether or not the particular decorating station is one of the chosen stations.

18. Ware decorating apparatus comprising a plurality of workpiece-supporting nests, linkage means for linking the nests together in a closed loop, drive means engaging the closed loop, for successively intermittently advancing the nests to successive dwells at a loading station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, interengageable nest locating means associated with each nest and with each decorating station and interengaging near the beginning of and disengaging near the end of said dwells and remaining disengaged between said dwells, means for centering the ware on the nests prior to reception of the ware at the decorating stations, a plurality of ware decorating units, including spraying units and stamping units, interchangeably mountable at each of the decorating stations, means associated with each of the decorating stations for activating the controlled operation of any decorating unit attached thereto in timed relationship to the intermittent advance of the closed loop of nests, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations each of said spraying units being appropriate for association with one of said chosen decorating stations and comprising a spray station which is positioned at such one associated decorating station, a cleaning station and a drying station arranged around a circle, a column in the center of said circle, arms radially projecting from said column each with its outer end positioned over one of said stations, a decoration-defining mask at the end of each arm and releasably and re-engageably held thereto by a magnetic coupling, means for intermittently rotating said column to advance said arms and said masks from said spray station to said cleaning station, from said cleaning station to said drying station

and from said drying station back to said spray station in endless succession, means to momentarily lower said column and release said magnetic couplings following each advance and to then again momentarily lower said column and reactivate said magnetic couplings just prior to the next -succeeding advance, the release of the masks occurring during dwell of ware at said spray station whereat ware is presented for receiving each mask released thereat, means for spray-coating said ware while it is covered with a mask, means at said cleaning station for containing a solvent for the spray coating for receiving and cleaning each mask released thereat, and means at said drying station for receiving and collecting solvent run-off from each mask released thereat, each of said 10 stamping units being appropriate for association with a decorating station other than one of said chosen stations and comprising a downwardly facing stamp underlain by a first relatively thin elastomeric material backed by a base of a second relatively thick elastomeric material, 15 said second elastomeric material being more readily compressed than said first elastomeric material whereby said stamp conforms to the surface of ware to be printed with minimized smudging despite slight variances in the shape and attitude of said ware, means for impressing 20 said stamp on ware during dwell of the ware thereunder, and means for inking the stamp between such impressions.

19. Ware decorating apparatus for applying desired combinations of decorations which may be programmed 30 in any desired order for any particular run of ware comprising a plurality of workpiece-supporting nests, linkage means linking the nests together in a closed loop, drive means engaging the closed loop for successively intermittently advancing the nests to successive dwells at a loading station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, interengageable nest locating means associated with each nest 35 and with each decorating station and interengaging near the beginning of and disengaging near the end of said dwells and remaining disengaged between said dwells, means for centering the ware on the nests prior to reception of the ware at the decorating stations, a plurality of ware decorating units, including spraying units and stamping units, interchangeably mountable at each of the decorating stations, means associated with each of the decorating stations for activating the controlled operation of any decorating unit attached thereto in timed 40 relationship to the intermittent advance of the closed loop of nests, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating 45 stations other than said chosen decorating stations each of said spraying units being appropriate for association with one of said chosen decorating stations and comprising at least one decoration-defining mask, means for laying said mask on passing ware after the dwell of the ware at the associated decorating station is initiated but before its associated chuck-rotating drive linkage is activated, for spraying a coating on the ware during activation of such associated chuck-rotating drive linkage, and for picking up said mask after termination of the activation of such associated chuck-rotating drive linkage but

prior to the termination of the dwell, and subsequently automatically cleaning the coating solution from said mask prior to re-use of said mask, each of said stamping units being appropriate for association with a decorating station other than one of said chosen stations and comprising a stamp, means for impressing said stamp on passing ware during dwell of the ware at the associated decorating station, and means for inking the stamp between such impressings.

20. Ware decorating apparatus for applying desired combinations of decorations which may be programmed in any desired order for any particular run of ware comprising a plurality of workpiece-supporting nests, linkage means for linking the nests together in a closed loop, drive means engaging the closed loop for successively intermittently advancing the nests to successive dwells at a loading station, a centering station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, interengageable nest locating means associated with each nest and with each of said decorating stations and said centering station and interengaging near the beginning of and disengaging near the end of said dwells and remaining disengaged between said dwells, means associated with the centering station for deactivating the ware gripping means associated with each nest toward the beginning of its dwell at said centering station and for reactivating said ware gripping means toward the end of said dwell, ware engaging members on opposite sides of the centering station and means moving them uniformly toward the center of said centering station into engaging relationship with ware positioned at said centering station between said deactivation and reactivation at said centering station of the ware gripping means associated with each nest whereby the ware is accurately centered on its nest and is then held in such centered condition, a plurality of ware decorating units, including spraying units and stamping units, interchangeably mountable at each of the decorating stations, means associated with each of the decorating stations for activating the controlled operation of any decorating unit attached thereto in timed relationship to the intermittent advance of the closed loop of nests, means associated with each one of said decorating stations for activating the chuck-rotating drive linkage of each nest during its dwell at the decorating stations, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations each of said spraying units being appropriate for association with one of said chosen decorating stations and comprising at least one decoration-defining mask, means for laying said mask on passing ware after the dwell of the ware at the associated decorating station is initiated but before its associated chuck-rotating drive linkage is activated, for spraying a coating on the ware during activation of such associated chuck-rotating drive linkage, and for picking up said mask after termination of the activation of such associated chuck-rotating drive linkage but prior to the termination of the dwell, each of said stamping units being appropriate for association with a decorating station other than one of said chosen stations and comprising a stamp, means for impressing said stamp on passing ware during dwell of the ware at the

associated decorating station, and means for inking the stamp between such impressings.

21. Ware decorating apparatus comprising a plurality of workpiece-supporting nests, linkage means for linking the nests together in a closed loop, drive means engaging the closed loop for successively intermittently advancing the nests to successive dwells at a loading station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, interengageable nest locating means associated with each nest and with each decorating station and interengaging near the beginning of and disengaging near the end of said dwells and remaining disengaged between said dwells, means for centering the ware on the nests prior to reception of the ware at the decorating stations, a plurality of ware decorating units, including spraying units and stamping units, interchangeably mountable at each of the decorating stations, means associated with each of the decorating stations for activating the controlled operation of any decorating unit attached thereto in timed relationship to the intermittent advance of the closed loop of nests, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations each of said spraying units being appropriate for association with one of said chosen decorating stations and comprising a spray station which is positioned at such one associated decorating station, a cleaning station and a drying station arranged around a circle, a column in the center of said circle, arms radially projecting from said column each with its outer end positioned over one of said stations, a decoration-defining mask at the end of each arm and releasably and re-engageably held thereto by a magnetic coupling, means for intermittently rotating said column to advance said arms and said masks from said spray station to said cleaning station, from said cleaning station to said drying station and from said drying station back to said spray station in endless succession, means to momentarily lower said column and release said magnetic couplings following each advance and to then again momentarily lower said column and reactivate said magnetic couplings just prior to the next-succeeding advance, the release of the masks occurring during dwell of ware at said spray station whereby ware is presented for receiving each mask released thereat, means for spray-coating said ware while it is covered with a mask, means at said cleaning station for containing a solvent for the spray coating for receiving and cleaning each mask released thereat, and means at said drying station for receiving and collecting solvent run-off from each mask released thereat, each of said last two named means including its own means for rotating mask-contacted elements associated with it during reception of each mask whereby cleaning is promoted by solvent agitation at the cleaning station without excessive splashing and spin drying occurs at the drying station, each of said stamping units being appropriate for association with a decorating station other than one of said chosen stations and comprising a downwardly facing stamp underlain by a first relatively thin elastomeric material backed by a base of a second relatively thick elastomeric material, said second elastomeric

material being more readily compressed than said first elastomeric material whereby said stamp conforms to the surface of ware to be printed with minimized smudging despite slight variances in the shape and attitude of said ware, means for impressing said stamp on ware during dwell of the ware thereunder, and means for inking the stamp between such impressions, said last named means comprising a platen, means to maintain the platen coated with ink, means for placing the platen under said stamp and for then touching the stamp against the platen and removing the platen all between said impressions whereby said stamp is subjected only to simple vertical translation during both inking and stamping to further minimize smudging.

22. Ware decorating apparatus for applying desired combinations of decorations which may be programmed in any desired order for any particular run of ware comprising a plurality of workpiece-supporting nests, linkage means for linking the nests together in a closed loop, drive means engaging the closed loop for successively intermittently advancing the nests to successive dwells at a loading station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, interengageable nest locating means associated with each nest and with each decorating station and interengaging near the beginning of and disengaging near the end of said dwells and remaining disengaged between said dwells, means for centering the ware on the nests prior to reception of the ware at the decorating stations, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations whereby ware being processed is positioned, at each of the several decorating stations, in centered attitude and is either rotated thereat from and to a defined datum rotative position or is maintained in said datum rotative position according to whether or not the particular decorating station in one of the chosen stations.

23. Ware decorating apparatus for applying desired combinations of decorations which may be programmed in any desired order for any particular run of ware comprising a plurality of workpiece-supporting nests, linkage means for linking the nests together in a closed loop, drive means engaging the closed loop for successively intermittently advancing the nests to successive dwells at a loading station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, interengageable nest locating means associated with each nest and with each decorating station and interengaging near the beginning of and disengaging near the end of said dwells and remaining disengaged between said dwells, means for centering the ware on the nests prior to reception of the ware at the decorating stations, a plurality of ware decorating units, including spraying units and stamping units, interchangeably mountable at each of the

decorating stations, means associated with each of the decorating stations for activating the controlled operation of any decorating unit attached thereto in timed relationship to the intermittent advance of the closed loop of nests, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations each of said spraying units being appropriate for association with one of said chosen decorating stations and comprising a plurality of spraying unit stations including a spray station which is positioned at the associated decorating station and a cleaning station and a drying station, three decoration-defining masks, means for laying each decoration-defining mask received at said spraying station on passing ware after the dwell of the ware at the associated decorating station is initiated but before its associated chuck-rotating drive linkage is activated, for spraying a coating on the ware during activation of such associated chuck-rotating drive linkage, and for picking up the particular mask after termination of the activation of such associated chuck-rotating drive linkage but prior to the termination of the dwell, means for immersing each decoration-defining mask received at said cleaning station in a solvent, means for spin-drying each decoration-defining mask received at said drying station, and means for successively intermittently advancing the masks to the spraying station, cleaning station and drying station in timed relationship with the intermittent advance of the closed loop of nests, each of said stamping units being appropriate for association with a decorating station other than one of said chosen stations and comprising a stamp, means for impressing said stamp on passing ware during dwell of the ware at the associated decorating station, and means for inking the stamp between such impressions.

24. Ware decorating apparatus for applying desired combinations of decorations which may be programmed in any desired order for any particular run of ware comprising a plurality of workpiece-supporting nests, linkage means for linking the nests together in a closed loop, drive means engaging the closed loop for successively intermittently advancing the nests to successive dwells at a loading station, a centering station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, locating pin sockets in each nest body; locating pins at each of said decorating stations and at said centering station and control means for extending them into said locating pin sockets at the beginning of said dwells and retracting them at the end of said dwells, means associated with the centering station for deactivating the ware gripping means associated with each nest toward the beginning of its dwell at said centering station and for reactivating said ware gripping means toward the end of said dwell, ware engaging members on opposite sides of the centering station and means moving them uniformly toward the center of said centering station into engaging relationship with ware positioned at said centering station between said deactivation and reactivation at said centering station of the ware gripping means associated with each nest whereby the ware is accurately centered on its nest and is then held in such

centered condition, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations whereby ware being processed is positioned, at each of the several decorating stations, in centered attitude and is either rotated thereat from and to a defined datum rotative position or is maintained in said datum rotative position according to whether or not the particular decorating station is one of the chosen stations.

25. Ware decorating apparatus comprising a plurality of workpiece-supporting nests, linkage means for linking the nests together in a closed loop, drive means engaging the closed loop for successively intermittently advancing the nests to successive dwells at a loading station, a centering station, decorating stations and an unloading station, each nest comprising a nest body, a rotatable ware chuck carried by the nest body and including ware gripping means, a drive linkage for rotating the chuck, and holding means for positioning the chuck at a datum rotative position with respect to the nest body when said drive linkage for rotating the chuck is not activated whereby said chuck is maintained in datum rotative position prior to and following rotation of the chuck, interengageable nest locating means associated with each nest and with each of said decorating stations and said centering station and interengaging near the beginning of and disengaging near the end of said dwells and remaining disengaged between said dwells, means associated with the centering station for deactivating the ware gripping means associated with each nest toward the beginning of its dwell at said centering station and for reactivating said ware gripping means toward the end of said dwell, ware engaging members on opposite sides of the centering station and means moving them uniformly toward the center of said centering station into engaging relationship with ware positioned at said centering station between said deactivation and reactivation at said centering station of the ware gripping means associated with each nest whereby the ware is accurately centered on its nest and is then held in such centered condition, a plurality of ware decorating units, including spraying units and stamping units, interchangeably mountable at each of the decorating stations, means associated with each of the decorating stations for activating the controlled operation of any decorating unit attached thereto in timed relationship to the intermittent advance of the closed loop of nests, means associated with each one of said decorating stations for activating the chuck-rotating drive linkage of each nest during its dwell at the decorating station, means to selectively program said last named means for effecting said activation of the chuck-rotating drive linkage of each nest only at one or more decorating stations which are chosen for a particular production run with ware carried in said nests remaining at said datum rotative position during their dwell at decorating stations other than said chosen decorating stations, each of said spraying units being appropriate for association with one

of said chosen decorating stations and comprising a spray station which is positioned at such one associated decorating station, a cleaning station and a drying station arranged around a circle, a column in the center of said circle, arms radially projecting from said column each with its outer end positioned over one of said stations, a decoration-defining mask at the end of each arm and releasably and re-engageably held thereto by a magnetic coupling, means for intermittently rotating said column to advance said arms and said masks from said spray station to said cleaning station, from said cleaning station to said drying station and from said drying station back to said spray station in endless succession, means to momentarily lower said column and release said magnetic couplings following each advance and to then again momentarily lower said column and reactivate said magnetic couplings just prior to the next-succeeding advance, the release of the masks occurring during dwell of ware at said spray station whereby ware is presented for receiving each mask released thereat, means for spray-coating said ware while it is covered with a mask, means at said cleaning station for containing a solvent for the spray coating for receiving and cleaning each mask released thereat, and means at said drying station for receiving and collecting solvent run-off from each mask released thereat, each of said last two named means including its own means for rotating mask-contacted elements associated with it during reception of each mask whereby cleaning is promoted by solvent agitation at the cleaning station without excessive splashing and spin drying occurs at the drying station, each of said stamping units being appropriate for association with a decorating station other than one of said chosen stations and comprising a downwardly facing stamp underlain by a first relatively thin elastomeric material backed by a base of a second relatively thick elastomeric material, said second elastomeric material being more readily compressed than said first elastomeric material whereby said stamp conforms to the surface of ware to be printed with minimized smudging despite slight variances in the shape and attitude of said ware, means for impressing said stamp on ware during dwell of the ware thereunder, and means for inking the stamp between such impressions, said last named means comprising a platen, means to maintain the platen coated with ink, means for placing the platen under said stamp and for then touching the stamp against the platen and removing the platen all between said impressions whereby said stamp is subjected only to simple vertical translation during both inking and stamping to further minimize smudging.

UNITED STATES PATENT OFFICE
CERTIFICATE OF CORRECTION

Patent No. 2,946,278

July 26, 1960

Howard B. Cummings

It is hereby certified that error appears in the printed specification of the above numbered patent requiring correction and that the said Letters Patent should read as corrected below.

Column 22, line 73, for "chunk" read -- chuck --; line 75, after "said" insert -- drive --; same line, for "chunk" read -- chuck --; column 27, line 17, for "loops" read -- loop --; line 59, for "memaining" read -- remaining --; column 30, line 32, after "means" insert -- for --; column 31, line 52, for "stations" read -- station --; column 32, line 12, for "psoitioning" read -- positioning --; line 32, for "menas" read -- means --.

Signed and sealed this 20th day of December 1960.
